No. 737,552.

PATENTED AUG. 25, 1903.

W. P. BOWERS.

RAIL JOINT.

APPLICATION FILED NOV. 5, 1902.

NO MODEL.

UNITED STATES PATENT OFFICE.

WILLIAM P. BOWERS, OF ESPLEN BOROUGH, PENNSYLVANIA, ASSIGNOR OF
ONE-FOURTH TO EDWARD J. HAMPTON, OF BRADDOCK, PENNSYLVANIA.

RAIL-JOINT.

SPECIFICATION forming part of Letters Patent No. 737,552, dated August 25, 1903.

Application filed November 5, 1902. Serial No. 130,133. (No model.)

To all whom it may concern:

Be it known that I, WILLIAM P. BOWERS, a citizen of the United States of America, residing at Esplen borough, in the county of Allegheny and State of Pennsylvania, have invented certain new and useful Improvements in Rail-Joints, of which the following is a specification, reference being had therein to the accompanying drawings.

10 This invention relates to certain new and useful improvements in rail-joints, the object of the invention being to provide a joint by means of which the rails may be securely held without the aid of bolts and nuts, as 15 now ordinarily employed, and also to provide a joint which will permit the removal of the rails without requiring the removal of the joint from the cross-ties.

Briefly described, my invention comprises 20 a rail-chair which consists of a base or saddle plate having an integral fish-plate and provided with an extension on which is slidably mounted a fish-plate to embrace the opposite side of the rail, means being provided 25 for securing the slidable fish-plate in position, said means being of such a nature as to permit the ready disengagement thereof to permit the sliding fish-plate being moved away from the rails in order that the latter may be 30 removed when desired.

In describing the invention in detail reference is had to the accompanying drawings, forming a part of this specification, wherein like numerals of reference indicate like parts 35 throughout the several views, in which—

Figure 1 is a side elevation of my improved rail-joint, showing the rail in position therein, the latter being in cross-section. Fig. 2 is a detail perspective view with the slidable 40 fish-plate and fastening therefor removed. Fig. 3 is a side view of the joint, showing all parts in position. Fig. 4 is a plan elevation of the securing-wedge for the slidable fish-plate. Fig. 5 is a like view of the locking-key 45 for same.

To put my invention into practice, I provide a base or saddle plate 1, which is adapted to be securely spiked to the cross-ties. (Not shown.) This saddle-plate has formed 50 integral therewith a fish-plate 2, which is adapted to embrace one side of the rails, and

the saddle-plate also has a table or bed plate 3, upon which the bases of the rails 4 are adapted to rest. This bed or table plate 3 carries an integral extension or tongue 5, the other or free end of which is flush with the one end of the saddle-plate 1, and this extension and also the saddle-plate 1 are provided with openings 6 7 in alinement with each other to receive the securing-wedge 8, which holds the 60 slidable fish-plate 9 in position. This slidable fish-plate is mounted on the extension or tongue 5, being slotted to receive said tongue or extension, and has a tongue 10, which engages in the space or groove 11, provided 65 therefor between the bed or table plate 3 and the base or saddle plate 1. The securing-wedge 8 is provided with a notch 12 and also has a plurality of openings or recesses 14, arranged at different heights on the face of 70 the plate and adapted to receive the wedge-shaped end 15 of the locking-key 16, by means of which the securing-wedge 8 is held in position.

The rail-chair is adapted to be spiked rigidly to the cross-tie, and to this end is provided adjacent each of its ends with openings 17 to receive securing-spikes. When the rail-chair has been placed in position on the tie and spiked thereon, the rails 4 are 80 placed in position on the table or bed plate 3, and the slidable fish-plate 9 is then placed on the tongue or extension 5 and slid up into position against the rails 4, and the securing-wedge 8 is then placed in position, as shown 85 in Figs. 1 and 2. The yoke 18 is then placed over the end of the tongue or extension 5, this yoke having a bed-plate 19, provided with openings which register with the openings 17 in one end of the base-plate 1, whereby the 90 same securing-spikes may be employed for securing the yoke in position. The yoke is provided with a partition 20, which forms two spaces 21, in which the locking-key 16 is held, this key being placed in either of the recesses, 95 according to which opening 14 may be in position to be engaged by the end of the key. The joint is also fastened down at this end by means of a clamp 22, which engages on top of the yoke 18 and has a spiked end 23 100 to engage in the cross-tie.

To remove the rails from the joint, a pinch-

bar may be engaged with the shoulder 24 of the locking-key 16 and this key forced out of engagement with the wedge 8, and the pinch-bar may then be engaged by the notch 12 of the wedge 8 and the latter drawn out of the openings 6 7, whereby the fish-plate 9 may be slid back in order to give sufficient clearance to remove the rails and place new rails in position, after which the fish-plate 9 may be slid up into position again and securely fastened.

When it is desired to renew the cross-tie, it will of course be necessary that the spikes be withdrawn, and at this time the clamp 22 may be readily withdrawn by engaging the pinch-bar under the shoulders 25 of said clamp.

It will be noted that various changes may be made in the details of construction without departing from the general spirit of my invention.

Having fully described my invention, what I claim as new, and desire to secure by Letters Patent, is—

1. A rail-joint comprising a base or saddle plate, a fish-plate formed integral therewith, a bed or table plate carried by the base or saddle plate, a tongue or extension carried by the table or bed plate and provided with an opening, a slideable fish-plate mounted on said tongue or extension, a yoke mounted on the base or saddle plate and engaging said tongue or extension, a securing-wedge engaging in the opening in the tongue or extension and in the opening in the base or saddle plate, and a clamp engaging the yoke and having a spiked end to engage in the cross-tie, substantially as described.

2. In a rail-joint, a base or saddle plate, an integral fish-plate carried thereby, a tongue or extension formed integral with the base or saddle plate and provided with an opening, a slideable fish-plate mounted on said tongue or

extension, a securing-key engaging in the opening of the tongue or extension, a yoke mounted on the outer end of said tongue or extension and adapted to be secured to the base or saddle plate, a locking-key mounted in said yoke and engaging the securing-wedge and the clamp engaging said yoke and having a spiked end to engage the cross-tie, substantially as described.

3. In a rail-joint, a base or saddle plate having an opening therein, an integral fish-plate carried thereby, a tongue or extension formed integral with the base-plate and having an opening therein, a fish-plate slidably mounted on the said tongue, a securing-wedge provided with a plurality of recesses adapted to be secured in the openings of the tongue and saddle-plate, a locking-key adapted to engage in one of the recesses of said wedge and means for securing the base-plate to the tie, substantially as described.

4. A rail-joint comprising a base-plate having an opening therein, an integral fish-plate carried thereby, a tongue formed integral with the base-plate provided with an opening therein in alignment with the opening in said base-plate, a fish-plate slidably mounted on said tongue, a yoke mounted on the base-plate engaging said tongue, a securing-wedge having recesses at different heights therein adapted to seat in the opening of the tongue and base-plate, a locking-key for securing said wedge in the openings, and means for securing the base-plate to the tie, substantially as described.

In testimony whereof I affix my signature in the presence of two witnesses.

WILLIAM P. BOWERS.
